BUBBLE BLOWING DEVICE

Fred A. Quinn, Jr., and Max Tryon,
Washington, D. C.

Application December 31, 1947, Serial No. 794,904

4 Claims. (Cl. 46—7)

1

This invention is an apparatus for blowing bubbles.

The principal object of the invention is to provide a bubble blower which produces a rapid and continuous succession of bubbles upon the application of air pressure to the device, and which is of simple and sturdy construction and capable of being produced in quantity at small cost.

Another object of the invention is to provide a bubble blowing apparatus wherein a large number of quite small bubbles are formed within the reservoir for containing the bubble solution, which small bubbles rise into the path of an air jet, which drives successive air films, supplied by the small bubbles, out through an exit pipe, to form a rapid succession of larger bubbles. The bubbles coming from the exit pipe will vary in size, depending on the strength of the air jet, the nature of the solution used and the dimensions of the several parts.

Another object of the invention is to provide a container serving as a reservoir for the bubble solution; two air streams are led into the container, one air stream being submerged below the level of the solution to form a large mass of small bubbles in the container, above the liquid level therein, which small bubbles rise into the path of an air jet above the liquid level in the container, this air jet driving successive films formed from the small bubbles, out through an exit pipe, these films forming a rapid succession of bubbles of larger size.

Another object of the invention is to provide a combined bubble blower and horn; the bubble blower is mounted inside the horn; blowing into the mouthpiece of the horn serves both to sound the horn and at the same time to form and project a succession of bubbles from the horn.

More particularly, the invention comprises a container of sufficient size to contain a substantial quantity of bubble forming solution. A branched air inlet pipe is fitted air tight into the container, one branch having its discharge opening submerged in the liquid, so that a large number of air bubbles are formed, which rise through the solution, tending to fill the upper part of the container. The other branch of the air inlet pipe is formed as an air jet, opening above the liquid level, in the zone filled with such bubbles. This air jet picks up and entrains a succession of films, formed from such bubbles and drives such films outwardly into the exit pipe, these films forming bubbles of various sizes, depending on the strength and

size of the air jet and the nature of the solution.

The invention provides an entertaining toy, and can be used for advertising purposes.

The general features of the invention having been thus outlined, it will now be described in more detail in connection with the accompanying drawings wherein:

Fig. 1 is a vertical side view, partly in section, of a bubble forming device in accordance with this invention.

Fig. 2 is a view similar to Fig. 1 showing a slight modification.

Fig. 3 is a longitudinal sectional view showing the bubble blower combined with a horn.

Fig. 4 is a vertical sectional view of another modification of the invention.

Referring now to these drawings, the bubble blowing device comprises a container 2 of any suitable material, such for example, as glass or plastic, which may be of elongated form as shown, for containing a substantial amount of bubble forming solution 4. An air pressure inlet pipe 6 is sealed into the container at 8 and is provided with a branch 10 having an exit 12 submerged in the solution, well below the liquid level therein. The upper branch 14 of the inlet pipe has a constricted nozzle 16 opening above the normal liquid level in the container, and directed into the exit pipe 18. Exit pipe 18 could be directed at any desired angle.

In operation, when the user blows into the pipe 6, some of the air escapes through the submerged opening 12, and as this air rises through the solution, forms a mass of relatively small bubbles 20 which substantially fills the container above the liquid level therein. These bubbles rise into the path of the air jet from 16, which entrains them and drives successive films supplied by such small bubbles, into and through exit pipe 18, forming bubbles 22 of various sizes. The operation is continuous and a steady succession of bubbles come from the exit pipe 18 as long as the air pressure is maintained.

The reservoir may, if desired, be provided with a filling opening, but a simpler way to replenish the supply of solution would be to immerse pipe 18 in a bubble solution and apply suction to pipe 6, or, conversely, pipe 6 could be immersed in the solution and suction applied to pipe 18. However, even a small supply of solution will supply bubbles continuously for many hours.

It should be understood that the size of the air exit opening 12 and air jet 16 may be varied, as desired, for varying the size of the bubbles

formed in the container and the size of the bubbles escaping from exit pipe 18. The stronger the air jet, the smaller are the bubbles. If the air jet is small as compared with submerged end 12 of pipe 10, bubbles tend to be larger. The size of the bubbles also varies with different bubble solutions.

In the modification shown in Fig. 2, the air jet branch 14', corresponding to branch 14 of Fig. 1, is provided with a venturi or similar restriction 24 of suitable size for increasing the velocity of the air jet that is directed into exit pipe 18.

Fig. 3 shows a modification of the invention, capable of use in the same way as the form shown in Fig. 1, but of simpler and cheaper construction and particularly adapted to fit inside of a toy horn. In this form, a cylindrical solution container 26 is provided with end plugs 28 and 30 which may be conveniently made of ordinary cork. An air inlet pipe 31, held in place by plug 31a, is fitted into plug 28 and is provided with a branch 32 opening below the level of solution 4 in the container. Pipe 31 is provided with a branch exit or jet opening 33 directed into one end of exit pipe 34 carried by the other plug 30. The parts just described are mounted in an ordinary toy horn 36, end plug 28 being of a size to make a substantially air-tight contact with the inside wall of the horn, air inlet pipe 31 being in the path of the blast of air coming from the usual mouth piece 38 provided with the usual vibrating reed or the like for sounding a note. A horn of this type is usually provided with a small sound exit opening 40. A positioning collar 41 may be used to support the right hand end of the cylinder 26. In Fig. 3, cylindrical reservoir 26 could be dispensed with, by combining plugs 30 and 41 into a single right hand plug through which tube 34 is passed, and by using 28 as a left hand plug, such right and left hand plugs defining a partly conical solution reservoir between them, filled by removal of a suitable filling plug.

In operation, when the user blows on the mouthpiece 38, some of the sound will come out of the hole 40, and air under some pressure will pass into pipe 31 and be forced below the level of the solution 4 to form a mass of small bubbles in the upper part of the container. The air jet from 33 entrains these small bubbles and drives a rapid succession of films, supplied by such bubbles, through exit pipe 34 to form a rapid succession of larger bubbles 42. In other words, when the user blows on the mouthpiece 38 he obtains, in addition to the usual musical note from the horn, a succession of bubbles from the large end of the horn, thereby providing an amusing and attractive toy.

The horn may be provided with a conical flanged member 44 to provide a catch chamber 46 for catching any drip that may escape from the bubble blower itself. Any accumulation of drip may be removed by removal of drain plug 48.

In the modification shown in Fig. 4, the bubble solution container 50 is provided with a snugly fitted but conveniently removable cover 52. In this cover is mounted an air pressure inlet pipe 54 having one branch 56 opening below the level of the solution and the other branch 57 forming a laterally directed air jet. This could have a Venturi restriction, if desired.

Mounted in the cover 52 is a vertically arranged open ended exit pipe or cylinder 58, with its

lower end immersed in the solution. Mounted in one wall of the pipe 58 is a smaller exit pipe 60 having its inlet in the path of the air jet from 57 and its upper or outer end 61 opening below the top of the larger pipe 58.

In operation, when air pressure is applied to pipe 54, some of the air escapes below the level of the solution, and forms a large mass of small bubbles which tend to fill the space below the cover 52 and come into the path of the air jet from 57. These small bubbles are entrained and driven by the air jet into tube 60, and form a succession of films which travel upwardly through exit tube 60 and form a steady succession of bubbles 62 leaving exit pipe 61. The formation of the bubbles as described is continuous, as long as pressure is applied to the pipe 54. In this form of the invention, the container may be refilled by lifting out cover 52 or by pouring solution down the tube 58. The purpose of the pipe 58 is to catch any drip or overflow from exit 61, and deliver it back into the container. Tube 58 could be omitted, if desired, and pipe 60 mounted in some other way. Pipes 60 and 58 could be directed at any desired angle, instead of vertically, as shown.

Any suitable type of bubble forming solution may be used, as desired. Where bubbles are desired that last a long time, a substantial quantity of glycerin may be used in the solution.

By providing a steady source of air pressure to the inlet pipe and means for continuously replenishing the supply of bubble solution, the stream of bubbles will be continuous, and could be used as an eye-catching advertisement, as in store windows, for example.

While the preferred and several embodiments of the invention have been described in detail, it should be understood that the invention is not to be limited to particular details, but may be carried out in other ways.

We claim as our invention:

1. Apparatus for blowing bubbles, comprising a reservoir for a bubble forming solution, a bubble exit pipe carried by said reservoir, an air inlet pipe positioned in said reservoir and having its inner end submerged below the level of the solution therein for thereby forming a succession of small bubbles which rise into the space above the solution, adjacent said exit pipe, a second air inlet pipe in said reservoir, opening above the liquid level therein, and directed toward said exit pipe, for supplying air for impelling said small bubbles formed by the first air inlet pipe into and through said exit pipe.

2. The combination as claimed in claim 1, wherein the described structure is mounted in an air actuated horn, with the outer end of the bubble exit pipe being directed out of the mouth of the horn, with said air inlet pipes positioned to receive air from the mouthpiece end of the horn.

3. Apparatus for blowing bubbles, comprising a reservoir for a bubble forming solution, a bubble exit pipe carried by the reservoir, an air inlet pipe positioned in said reservoir, provided with two branches, one branch opening near the bottom of the reservoir and so normally immersed in the bubble forming solution, and operating to release air below the level of the solution to cause a succession of small bubbles to rise into the space adjacent said exit pipe, the other branch of the inlet pipe opening above the liquid level in the reservoir and being directed toward said exit pipe,

for supplying air for impelling said small bubbles into and through said exit pipe.

4. The combination as claimed in claim 3, wherein the described structure is mounted in an air actuated horn, with the outer end of the bubble exit pipe being directed out of the mouth of the horn, said air inlet pipe positioned to receive air at the mouthpiece end of the horn.
